SELF-CLOSING TUBE

Garfield Abarr, Napa, Calif.

Application July 22, 1949, Serial No. 106,132

4 Claims. (Cl. 222—213)

1

This invention relates to self-closing tubes and particularly to tubes of this character which are particularly adapted to contain tooth paste, shaving cream, jellies, glue, cement, or any like material.

In the past, various types of tubes and containers for these materials have been placed upon the market. Some of these tubes have been of readily deformable material and all of them have been provided with discharge orifices. Sometimes the discharge orifices are closed with a removable cap member. Devices of this character, while having been widely used, have been subject to the difficulty that loss of the removable cap makes it difficult if not impossible properly thereafter to cover the discharge orifice. In that event, certain products such as glue, cement, etc. which harden upon contact with the atmosphere, clog the discharge orifice and render further utilization of the contents in the tube practically impossible or, at least, difficult. Furthermore certain products such as tooth paste, shaving cream and certain jellies will disintegrate upon contact with the atmosphere.

Various other types of closure members have been provided for deformable tubes including hinged devices which overcome the difficulty of the closure member becoming lost but which are difficult or expensive to manufacture. This difficulty and expense has prevented their widespread use.

Various other types of devices have been proposed and a variety of valves, plugs, and other apparatus have been incorporated in containers of this character with varying degrees of success and with varying numbers of defects.

It is an object of this invention to provide a device of this character which is self-closing and which is self-contained.

It is a further object of this invention to provide a device of this character which is always ready for use and which requires no operation of caps, hinges, valves, plugs or other devices.

It is a further object of this invention to provide a tube which is always closed, except when in operation, whereby the contents of the same will not be dried out by contact with the atmosphere.

Other objects and advantages of the present invention will appear from the following specification taken in conjunction with the accompanying drawings in which:

Figure 1 represents a side elevational view of a self-closing tube incorporating my invention.

Figure 2 represents a cross-sectional view taken along the line 2—2 of Figure 3.

2

Figure 3 represents a cross-sectional view taken along the line 3—3 of Figure 1.

Figure 4 represents a top plan view when the tube is closed.

Figure 5 represents a top plan view when the tube is open.

As is shown in Figure 1 my device consists of a tube 10 which may be formed of any flexible or resilient material such as natural or synthetic rubber, flexible plastic or other material having these qualities. The upper end 11 of the tube 10 incorporates the self-closing assembly which will more fully hereinafter be described and the lower end 12 is crimped in the conventional manner to prevent the discharge of the contents of the tube through the other end.

As is shown more clearly in Figures 2 and 3, the discharge end 11 of the tube 10 is provided with a thickened portion 13 substantially as shown.

20 The thickened portion 13, being molded integrally with the remainder of the tube 10, is made of the same material as the tube 10, that is, either plastic or rubber or suitable similar material, and differs from the rest of the tube only because of its increased thickness.

This increased thickness will cause the portion 13 of the tube 10 to be less readily deformable than the remainder of the tube. As is shown more particularly in Figure 3 the lower portion 13a of the thickened portion 13 extends substantially about the entire circumference of the tube and then tapers upwardly to two pairs of ribs 14 providing three channels 16, 17 and 18. The two pairs of ribs 14 are in registry (as shown) so that ribs 14a engage ribs 14b, as illustrated in Figures 2 and 5. The channels 16, 17 and 18 merge into a common chamber 19. As is particularly shown in Figures 2 and 5 the thickened portions 14a and 14b provide a pair of rockers or shoulder members at fulcrum point 20

30 whereby when pressure is exerted upon the thickened portion 13 at, for example, 13a, the thickened portions 14a and 14b rock about fulcrum point 20 and that portion of the discharge end 11 above the point 20 will tend to be drawn apart.

40 The channels 16, 17 and 18 which extend upwardly and merge at chamber 19 are closed by a pair of lips 21 and 22 which are likewise formed of resilient rubber and are molded integrally with the remainder of the tube 10. The lips 21 and 22

50 provide a discharge orifice 23 between them and are normally in closed position since, in the first place, they are molded in that position, and secondly, because the remainder of the device is normally molded in the condition shown in Figures 1,

55 2, 3 and 4. As has previously been pointed out

the thickened portion 13 is substantially circumferential and, being less resilient than the remainder of the tube 10, will urge the tube to the position illustrated in Figure 1.

Likewise, when the tube is squeezed at points 13a, for example, and opposing portions of member 13 are urged together, the members 14 pivot around the point 20. Two things will then occur. In the first place the lips 21 and 22 will be urged apart and the orifice 23 will be opened, generally as shown in Figure 5. In the second place, the volume of the tube 10 will be decreased causing a discharge of the contents of the tube 10 through the channels 16, 17, 18 and outwardly through the orifice 23.

Operation of the device may briefly be described as follows: Let it be assumed that the tube 10 is completely filled with tooth paste, shaving cream, jelly, salve, glue, cement, or any like material and that the bottom 12 is properly crimped to prevent the discharge of the contents therethrough. In this condition the lips 21 and 22 will normally be in closed position as shown in Figures 1, 2, 3 and 4, and the tube will be in the expanded position shown in the same figures. However, when pressure is applied to the portions 13a of the tube 10, the thickened members 14 will, as shown in Figures 2 and 5, rock about the point 20 with the result that the lips 21 and 22 will be separated and the orifice 23 opened. In addition, the volume within the tube 10 will be decreased and the contents of the tube will seek an outlet. Since an outlet has been prepared by the opening of the orifice 23, the contents of the tube will be discharged therethrough. As the tube contents are used, the tube may be rolled up from the bottom as is done in conventional tubes. When the tube contents are nearly exhausted waste may be avoided by squeezing the tube nearly flat at point 13a. This is possible due to flexibility of material used in construction.

When the pressure upon the point 13a is reduced, the effect of the thickened or less resilient portion 13 will be to urge the tube to the position shown in Figure 1, that is, with the portion 13 in normal fully extended position. The shoulders 14 will pivot at the point 20 and the lips 21 and 22 will close with the result that the discharge outlet 23 will likewise be closed.

The tube may be formed in any suitable manner as either by molding the same in entirety at one time or by molding the same in two halves 24 and 26 and sealing them at their adjoining edges in any suitable manner as by cementing them, fusing them, or vulcanizing them.

In addition, at the time the tube is formed the lips 21 and 22 may be molded together in closed position. This may be desirable where the tubes are to be roughly handled prior to their being distributed to the ultimate consumer and where unexpected pressure might be applied to the tube 10 during transit, etc. Assuming that the lips 21 and 22 are molded in a sealed condition it is obvious that the contents of the tube 10 may not be discharged by such pressure. However, the ultimate consumer may remove the seal. In the event the seal is a simple rubber diaphragm between the lips 21 and 22 the ultimate consumer may remove the diaphragm or make a slit therein.

It will be seen from the foregoing that I have

invented a self-closing tube which will retain itself in normally closed position preventing the drying of the contents of the tube by the loss of one or more parts of the same.

While I have shown the preferred embodiments herein it is not to be assumed that the particular modification disclosed herein is the only manner of utilizing my invention. I assume for example that in the event merely increasing the thickness of the tube 10 at points 11 and 13 is insufficient to secure the desired results, a more rigid type of material may be molded into the tube at those portions generally designated at 13 and 14. In this event it will be obvious that sufficient rigidity will be imparted to the portion 13 and 13a and to the shoulders 14 to obtain the rocker effect (as indicated in Figure 2) to compress the tube 10 and urge its contents outwardly through the opened discharge orifice 23.

20 I claim:

1. In a self-closing tube formed of resilient material, a pair of lips forming a discharge orifice, said lips being normally in closed position, a laterally disposed rib extending around 25 the inner circumference of said tube and two pairs of longitudinally disposed ribs extending from said laterally disposed rib toward said lips, each pair of said longitudinal ribs engaging at a point adjacent said lips, said longitudinal ribs 30 also forming channels from the area within said tube to said lips.

2. In a self-closing tube formed of resilient material, a pair of lips forming a discharge orifice, said lips being normally in closed position, 35 a circumferential rib extending laterally around the inside of said tube, two pairs of longitudinally disposed rocker-shaped ribs extending from said laterally disposed rib toward said lips, each pair of opposite longitudinal rocker-shaped ribs engaging at a point adjacent said lips and adapted to rock with respect to each other, said longitudinal ribs also forming channels from the area within said tube to said lips.

3. In a self-closing tube formed of resilient 45 material, a circumferentially disposed lateral rib normally urging said tube to full extended position, two pairs of longitudinally disposed rocker-like ribs extending from said circumferentially disposed ribs to one end of said tube, a pair of lips 50 in said end of said tube, each pair of said longitudinal ribs being in engagement and forming a shoulder about which they may rock with respect to each other, whereby, when one end of said pairs of rocker-like ribs are urged toward each other, the other ends of said ribs are urged apart.

4. In a self-closing tube formed of resilient material, a circumferentially disposed lateral rib normally urging said tube to full extended position, 60 two pairs of longitudinally disposed rocker-like ribs extending from said circumferentially disposed rib to one end of said tube, a pair of lips in said end of said tube forming a discharge orifice, each pair of said longitudinal ribs being in engagement and forming a shoulder about 65 which they may rock with respect to each other, whereby, when one end of said pairs of ribs are urged toward each other, the other ends of said ribs and said lips are urged apart.
